CLAIM

The ornamental design for a desk, as shown and described.

DESCRIPTION

FIG. 1 is a back top left side isometric view of a desk showing my new design with the desk surfaces rotated into closed positions;

FIG. 2 is a back elevational view thereof;

FIG. 3 is front elevational view thereof;

FIG. 4 is a top view thereof;

FIG. 5 is a bottom view thereof;

FIG. 6 is a right side view thereof, the left side being a mirror image thereof;

FIG. 7 is a back top left side isometric view of the desk showing my new design with the desk surfaces rotated into open positions;

FIG. 8 is a back elevational view thereof;

FIG. 9 is front elevational view thereof;

FIG. 10 is a top view thereof;

FIG. 11 is a bottom view thereof; and,

FIG. 12 is a right side view thereof, the left side being a mirror image thereof.
